UNITED STATES PATENT OFFICE.

CHARLES STREIT, OF CINCINNATI, OHIO.

IMPROVEMENT IN EXTENSION LOUNGES.

Specification forming part of Letters Patent No. 123,649, dated February 13, 1872.

SPECIFICATION.

I, CHARLES STREIT, of the city of Cincinnati, county of Hamilton and State of Ohio, have invented certain Improvement in "Extension Lounge," of which the following is a specification.

Nature and Object of the Invention.

The improvement of an "extension lounge" embodied in my invention relates to the construction of the same, in such a manner that when the main body or visible seat of the lounge (when closed) is opened or extended, a second seat, which is sunk underneath the same, is discovered, which can be raised to the same height of the extended portion, thus doubling the width of the lounge.

Description of the Accompanying Drawing.

Figure 1 is a perspective view of an extended lounge embodying my invention. Fig. 2 is a section of the same, showing the respective situation of the rear frame when raised, and also (in dotted outline) when sunk. Fig. 3 is an end view of the rear frame, together with the brace supporting the same, when raised.

General Description.

A is the extension part of the lounge, with its face-frame and slats G and a combining brace, H. This part slides on the blocks and rollers E, and is steadied by the turning slat F. B

is the rear or movable frame, which is sunk below when the lounge is closed, and which may be raised by aid of straps I and J, as follows: Strap I is raised perpendicular until brace C slides down upon its hinges and rests solidly on the brace D; then strap J is also lifted to the height of the foot-rail K, and then it is drawn downward a few inches, so that the foot end rests on said foot-rail. The rear frame is sunk again by drawing the strap I in a slight angle toward the side of the head-rest, when the foot-end will slip down and the main brace C will turn upon its hinges, thus sinking the whole of the rear frame. The covering of the lounge may consist of a spring mattress, plain mattress bed, or in any other manner desirable.

Claims.

I claim as my invention—

1. The combination of the stationary frame of a lounge having brace D with the sinking frame B, having hinged brace C, and the sliding frame A, provided with blocks and rollers E, all constructed and operating substantially as described.

2. The combination of the swinging slat F, with the devices of the first claim, for the purpose described.

Witnesses: CHARLES STREIT.
